(57) **CLAIM**

The ornamental design for a cosmetic spoon, as shown and described.

DESCRIPTION

FIG. 1 is a top perspective view of a first embodiment of a cosmetic spoon;

FIG. 2 is a front view of the cosmetic spoon shown in FIG. 1;

FIG. 3 is a back view of the cosmetic spoon shown in FIG. 1;

FIG. 4 is a right side view of the cosmetic spoon shown in FIG. 1;

FIG. 5 is a left side view of the cosmetic spoon shown in FIG. 1;

FIG. 6 is a top view of the cosmetic spoon shown in FIG. 1;

FIG. 7 is a bottom view of the cosmetic spoon shown in FIG. 1;

FIG. 8 is a top perspective view of a second embodiment of a cosmetic spoon;

FIG. 9 is a front view of the cosmetic spoon shown in FIG. 8;

FIG. 10 is a back view of the cosmetic spoon shown in FIG. 8;

FIG. 11 is a right side view of the cosmetic spoon shown in FIG. 8;

FIG. 12 is a left side view of the cosmetic spoon shown in FIG. 8;

FIG. 13 is a top view of the cosmetic spoon shown in FIGS. 8; and,

FIG. 14 is a bottom view of the cosmetic spoon shown in FIG. 8.

The dashed lines in FIGS. 8, 9, and 11-13 are included for the purpose of illustrating a portion of the cosmetic spoon that forms no part of the claimed design.

1 Claim, 8 Drawing Sheets
